UNITED STATES PATENT OFFICE.

JOSEPH R. MITCHELL AND FRANK X. FISCHER, OF SAN FRANCISCO, CAL.

BOILER.

SPECIFICATION forming part of Letters Patent No. 269,308, dated December 19, 1882.

Application filed May 22, 1882. (No model.)

To all whom it may concern:

Be it known that we, JOSEPH R. MITCHELL and FRANK X. FISCHER, of the city and county of San Francisco, State of California, have 5 invented an Improved Boiler; and we do hereby declare the following to be a full, clear, and exact description thereof.

Our invention relates to certain improvements in engine-boilers; and it consists in certain details of construction which will be more fully explained by reference to the accompanying drawings, in which—

Figure 1 is a longitudinal vertical section. Fig. 2 is a transverse section through the front 15 of boiler. Fig. 3 is a transverse section through the middle of boiler. Fig. 4 is a transverse section through the combustion-chamber. Fig. 5 is a detail of construction.

A is the cylindrical shell of our boiler, which 20 is intended to be mounted upon wheels and be portable. From the sides of the cylinder double walls B extend downward, forming pendulous water-legs, and have a bottom uniting them at such a distance below the boiler 25 as to form an independent chamber, the front portion of which forms a fire-box and ash-pit, with a hollow tubular water-bridge wall or drum, C, at its rear end, suitably connected with the boiler by pipes, so as to provide a 30 circulation through it. The flame and products of combustion pass over the bridge-wall and beneath the boiler and into a rear combustion-chamber, D, from which they return to the front through tubes E, extending through the 35 boiler, and escape through the chimney F. The bottom is formed in three sections, G H I, the section G being bolted beneath the ash-pit, and being removable to give access to it. The second section, H, occupied the middle portion, 40 and is also removable to inspect the circulating-pipes. The rear section, I, is that portion resting upon the bolster, and is not removable. The walls B have plates B' bolted to their rear 45 ends and extending toward the rear, forming an incline outward from top to bottom, as shown. The bottom plate, G, is also extended backward and turned up at the rear, and with these extended sides forms the ash-pit. A plate, J, extends downward from the drum C 50 to the floor, to prevent the passage of an air-current beneath the drum, and the front end

of the floor is stiffened by transverse angle-irons K, which are bolted to it. These angle-iron braces also serve to form a fire-proof joint where the bottom sections, G H I, meet by 55 lapping over them, and they retain a sufficient amount of ashes between them to keep the bottom protected from too much heat.

The bolster L extends across beneath the end of the combustion-chamber, and is suitably 60 secured to the bottom plate, and the axle M turns upon the king-bolt N, as shown. A piece of angle-iron, O, is bolted across the bottom outside, and corresponding with one of the inner angle-irons, to give the bottom extra stiffness and serve as a point for the attachment 65 of brace P for the king-bolt. The ends of the bolster L project beyond the sides of the water-legs, and both it and the axle Q have braces R, extending up on each side to the cylindrical 70 shell of the boiler, where their upper ends are securely bolted. This is to stiffen the water-legs and prevent the straining of the rivet-joint by the side swing or surge of the engine and boiler in passing over uneven ground. Boilers 75 made with pendulous water-legs, as shown in this case, and having no solid fire-front, are very easily loosened at the rivet-joints if not very firmly braced, and these braces R strengthen them at this point. At the point where the 80 rear axle passes through the plates B' they are strengthened and relieved from strain by the plates S, which are bolted or riveted to the outside of the water-legs B and walls B'. These plates are notched at T to fit over the 85 axle, and caps or clamps U extend below the axles and are drawn up firmly against them by bolts u, which are tapped into the lower edges of the plates S, these latter being made of considerable thickness for that purpose as 90 well as to give the requisite strength. By this combination of braces and castings the water-legs are rigidly held in position and the joints kept tight. The bottom of the ash-pan is inclined upward toward the front, so that the 95 brake-bar X may pass beneath it and stand the same distance from the ground as the rear end of the ash-pan. This is necessary, because the ash-pan is so near the ground that with any other construction the brake-bar would 100 strike. The rear axle is preferably bent or cranked so as to pass above the furnace-door.

The drum C extends across the space between the water-legs below the cylindrical shell of the boiler, as shown, and the feed-water pipe V is placed opposite the drum, so as to feed water directly into it, thereby avoiding the risk of cracking the furnace-sheet, which occurs when the feed-water is pumped directly into the water-legs and impinges against the sheet. The circulation and blow-off pipe W extends 5 forward from the drum, and a vertical pipe, W', extends from the bottom of the boiler-shell down through the bottom of the furnace, where a blow-off valve is fixed, thus making a simple and effective arrangement for the circulation and blow off. The rivet-joints of the water-legs B are protected from the heat in the combustion-chamber by liners or plates *a*, which are riveted over them with an air-space between. 10 Having thus described our invention, what we claim as new, and desire to secure by Letters Patent, is—

1. In a portable boiler having the pendulous water-legs B and wheel-axes, as shown, the inclined braces R, extending upward from the bolster and rear axle, respectively, and secured to the boiler-shell, substantially as and for the purpose herein described. 15
2. In a portable boiler having the pendulous water-legs and the closed bottom, as shown, the walls B, having the supplemental plates B', extended back from the vertical plane of the boiler-head, in combination with the floor-plate G, extended back to the same point and turned up, substantially as and for the purpose herein described. 20
3. In a portable boiler having pendulous water-legs, and the axle Q, passing through the plates B' in rear of the furnace, the plates

S, notched to fit the axle and bolted to the 40 walls B' in combination with the caps U and bolts *u*, substantially as and for the purpose herein described.

4. In a boiler, and in combination with the pendulous water-legs B, the inclined bottom 45 plates, G H I, formed in sections and secured independently of each other, substantially as herein described.

5. In a boiler having the pendulous water-legs B and sectional bottom G H I, the transverse angle-irons K, bolted to the bottom plates, substantially as and for the purpose herein described. 50

6. In a boiler having the walls B, bottom plates, G H I, and the fixed axle Q, and the 55 axle M, with its bolster N and king-boil brace P, the exterior angle-iron, O, and the corresponding interior angle-iron, K, bolted to the bottom and having an attachment for the brace, substantially as herein described. 60

7. The boiler A, with the water-legs B and the transverse connecting-drum C, in combination with the horizontal pipe W, extending forward beneath the boiler, and the vertical pipe W', connecting with its front end, and 65 having a cock or valve to discharge or blow off beneath, substantially as herein described.

8. The protecting plates or liners *a*, extending over the rivet-joints of the water-legs B within the rear combustion-chamber, substantially as herein described. 70

In witness whereof we have hereunto set our hands.

JOSEPH R. MITCHELL.
FRANK X. FISCHER.
